UNITED STATES PATENT OFFICE.

WHILLDIN FOSTER AND EUGENE C. FOSTER, OF PHILADELPHIA, PENNSYLVANIA, ASSIGNEES
TO LEEDS PROCESS COMPANY, A CORPORATION OF NEW JERSEY.

OIL-ATOMIZER.

No. 872,649.

Specification of Letters Patent.

Patented Dec. 3, 1907.

Application filed May 7, 1906. Serial No. 316,570.

To all whom it may concern:

Be it known that we, WHILLDIN and EUGENE C. FOSTER, citizens of the United States, residing at Philadelphia, in the county of Philadelphia and State of Pennsylvania, have invented certain new and useful Improvements in Oil-Atomizers, of which the following is a full, clear, and exact description.

10 Our invention relates to an apparatus for atomizing oil, and pertains particularly to the injection and atomizing of oil in a gas producer for the purpose of making illuminating or other gas.

15 The principal object of the invention is to provide a combined oil injector and atomizer which is capable of completely breaking up or atomizing oil of all grades and characters.

20 A further object of the invention is to provide a simple structure in which the oil, and the various atomizing steam jets, are independently adjustable, and in which only a minimum body of oil is exposed to the heat 25 of the furnace prior to its atomization.

With these and other objects in view our invention consists in the construction, combination, in the location and in the arrangement of parts, as hereinafter set forth and shown, and finally particularly pointed out in the appended claims.

30 In the drawings: Figure 1 is a side view of an atomizer embodying the principles of our invention; Fig. 2 is a longitudinal sectional view of the same; Fig. 3 shows a face view of one of the parts; Fig. 4 is a similar view of the other part; Fig. 5 is a section on the line V—V of Fig. 3; Fig. 6 is a detail view showing part of the adjusting means; Fig. 7 is a 35 section on the line VII—VII of Fig. 4; Fig. 8 illustrates a slightly modified form of construction; Figs. 9, 10 and 11 are various perspective views of the parts of the apparatus employed in the construction of Fig. 8.

40 Among the processes for the manufacture of illuminating and other gases, the method involving the disassociation of crude oil and steam by heat and allowing the elements to re-combine as a gas, plays an important part. A highly heated chamber is ordinarily used into which the oil and steam are injected, and where they are disassociated, and reduced to their component elements by the 45 heat of the chamber, and the fire brick checker work which is ordinarily employed.

In order to have this process successful it is important that the oil is very finely atomized and mixed with steam before it is subjected to the heat, since otherwise the oil would have its more volatile products distilled away, leaving a tarry residue which could not be atomized, or made into a gas. In practice, the oil must be broken up into particles so exceedingly minute that they are completely reduced and disassociated 60 into their component elements almost immediately upon reaching the heat zone of the furnace chamber in which the process takes place. In carrying out our present invention we aim to secure this result.

70 Referring to the drawings and to the various views in which like parts are designated by the same reference sign, 1 denotes the casing, preferably cylindrical in form, and screw threaded at 2, so as to be received into 75 the wall of a furnace chamber, or in any desired relation. The casing 1 is made hollow, and its inside surface or wall 3 is preferably smooth and straight throughout the whole or part of its length so as to constitute a 80 guide for certain movable parts or members hereinafter described. We prefer to make the interior surface 3 of circular section, as this form is most convenient to manufacture.

85 Within the casing 1 are contained a pair of movable parts 4 and 5, of which 5 constitutes what I shall term the steam delivery chamber, while the part 4 constitutes the oil delivery chamber. These parts are both conveniently made of semi-cylindrical form, 90 as shown in Figs. 5 and 7, so that when they are assembled together they will be closely received and guided by the surface 3 of the casing 1. 6 denote tenons or guides adapted to be slidably received in the grooves or 95 mortises 7, of the other member.

The oil delivery chamber 4 is drilled or apertured throughout its length with a conical or tapering hole 8, and a correspondingly coned or tapering plug 9 is arranged to be 100 closely received within the tapered hole 8.

100 10 denotes a rod or stem by which the plug 9 is longitudinally moved.

105 11 indicate ducts or apertures communicating with the tapering hole 8 and terminating in the face 12 of the oil delivery chamber. Where the ducts 11 issue we provide in practice rifles or scallops 13, as clearly shown in Fig. 2. The arrangement is such that when the plug 9 is in its right hand or 110

withdrawn relation, a space is left through which the oil may flow and issue through the various ducts 11. When the plug 9 is moved to the left, the space is entirely closed up 5 and no oil can flow through the ducts 11, nor remain in any part of the oil delivery chamber.

For the purpose of moving the plug 9 we arrange a handle 14 upon the rod 10, which 10 runs through a stuffing box or gland 15, on a pipe 16, forming a continuation of the oil delivery chamber 4.

17 indicates a branch connection leading to any source of oil supply (not shown).

15 The steam delivery chamber is longitudinally drilled or apertured, as shown at 18, and is provided with a number of nozzles 19, issuing through the flat face 20 of the steam delivery chamber. The arrangement of the 20 various nozzles 19 is such that they deliver against the riffles 13 previously mentioned, and the jets are deflected thereby, so that the steam current flows tangentially past the various oil ducts 11.

25 The oil delivery chamber and the steam delivery chamber are capable of being adjusted with relation to one another so that the relation of the steam jets to the oil ducts can be varied. For this purpose the steam 30 delivery chamber has an extension 21 thereon, the end of which is concaved to fit into a groove 22, of a nut 23, which moves on the threaded stud 24, projecting from the oil delivery chamber. By turning the nut, the 35 two chambers are moved in and out relatively to one another.

In addition to the steam passage 18, we provide additional passages for superheated or other steam or gas in both the oil and the 40 steam delivery chambers. These passages are indicated in dotted lines at 25 and 25' respectively, and terminate in transverse cavities 26 and 26', having delivery nozzles 27, and 27'. These nozzles issue on bevel 45 portions 28 of the respective chambers by which the steam jets impinge against the stream of mixed oil and steam coming from the ducts 11 and nozzles 19. This stream normally passes outward in a flat sheet from 50 between the ends of the chambers 4 and 5.

The use and operation will be readily understood from the preceding description. The handle 14 is adjusted so that a space is left between the plug 9 and its conical hole 8, 55 through which oil flows and issues through the ducts 11. The steam jets from the nozzles 19 aspirate the oil from the ducts 11, and the combined current issues in a flat stream from between the ends of the chambers as above stated. At this point the 60 stream meets the violent jets from the nozzles 27 and 27', which serve to render the atomization absolutely complete in case this was not previously accomplished. At the 65 same time the amount of steam added is

made suitable to the requirements of the gasifying process. It will be seen that the oil flow is minutely controllable by the handle 14, and the steam flow is, of course, regulated by throttling the steam supply to the 70 various steam passages.

In Figs. 8 to 11 inclusive, we have illustrated a slightly different form of construction in which not only are the atomizing steam jets adjustable with relation to the oil 75 ducts, but the additional steam jets, which finally complete the atomizing process, are also adjustable with relation to the others. For this purpose we make use of three chambers. 30 is the oil delivery chamber, having 80 an oil cavity 31, and oil delivery ducts 32 leading therefrom. 33 is the initial steam delivery chamber, having a cavity 34, and steam nozzles 35, which are inclined so as to deliver a stream in a partly tangential direction over the oil ducts 32. Referring to Figs. 10 and 11, it will be seen that the end of the chamber 30 is recessed or chamfered at 36. The member 33 has a ledge or protuberance 37 thereon, which fits the chamfered 90 portion 36 of the opposed member. When the members are assembled, a diagonal gap or opening 38 is produced, the width of which can be regulated by varying the relation of the two chambers. 39 denotes the 95 secondary steam delivery chamber which has a cavity 40, and a delivery opening 41, inclined with respect thereto, and with respect to the opening 38 above mentioned. Both of the steam delivery chambers 33 and 39 100 are adjustable with respect to the oil delivery chamber 30 by any means, as for example, by grooved screws 42 coöperating with a yoke 43, fixed to the member 30. The various chambers 30, 33 and 39 have 105 threaded inlets 44, 45 and 46, by which any flexible or convenient pipe connections are made to suitable sources of supply. The operation of this form of my invention will be sufficiently obvious without detailed description. The oil issues from the ducts 32 and is carried away by the steam jets from the nozzles 35. As the combined stream of steam and oil issues from the opening 38, it is impinged against and completely atomized and 110 broken up by the jet of steam from the opening 41. The various chambers are adjusted so as to get the best effects.

An important feature of the invention lies in the arrangement by which any dripping 120 away or loss of the oil is completely prevented. It will be observed that in both forms of construction a drip tray is formed in which any surplus drops of oil are caught and immediately afterward atomized by the steam 125 jets. In the structure of Figs. 1 to 7 inclusive the scallops or riffles 13 are depressed slightly below the plane of the surrounding edge. Any surplus oil is thereby prevented from escape and is exposed to the steam 130

blast in the same way as the oil in the ducts. In the form of the invention shown in Figs. 8 to 11 inclusive the oil from the ducts 32 may drip into the depressed face of the steam chamber where it is of course immediately exposed to the steam blast. In both cases it is essential that the atomizer be horizontally disposed to get the best effects.

What we claim, is:—

- 10 1. An oil atomizer having an oil chamber with delivery ducts, and a steam chamber with delivery nozzles, both of said chambers having additional nozzles for directing jets of steam against the combined flow from said ducts and first named nozzles.
- 15 2. An oil atomizer having an oil chamber and a steam chamber both of semi-cylindrical form, a hollow casing formed to receive and guide said chambers so as to permit longitudinal adjustment with respect to one another, said chambers having delivery ducts and nozzles for the exit of steam and oil therefrom.
- 20 3. An oil atomizer having a pair of chambers each formed with a cavity, ducts and nozzles issuing from the respective cavities, and additional cavities in both chambers having nozzles for the delivery of steam against the combined flow from said ducts and first named nozzles.
- 25 4. An oil atomizer having a pair of semi-cylindrical chambers, means for guiding said chambers with their flat faces in juxtaposition to one another so as to permit longitudinal adjustment, and ducts and nozzles in said flat faces directed at an angle to one another.
- 30 5. An oil atomizer having an oil delivery chamber with a coned or tapering cavity therein, a plug formed to be closely received in said cavity, oil delivery ducts leading from said cavity, and means for impinging jets of steam across the path of delivery of said ducts.
- 35 45 6. An oil atomizer comprising a pair of chambers having a pair of flat faces arranged
- in juxtaposition to one another, ducts and nozzles in said faces and arranged to cause a mixed current of steam and oil to issue at the end of the chambers and between their flat faces, and means for directing jets of steam against such mixed current at a point beyond the end of the chambers.
7. An oil atomizer having a pair of chambers with flat faces in juxtaposition to one another, and bevel ends, ducts and nozzles in the respective flat faces, and additional nozzles in said bevel ends for the delivery of steam.
8. An oil atomizer having an oil chamber with a conical or tapering cavity therein, a plug formed to fit said cavity and adjustable longitudinally thereof, oil delivery ducts extending from said cavity, and means for directing steam jets across the path of delivery of said ducts.
9. An oil atomizer having an oil delivery chamber with a conical or tapered cavity therein, a plug formed to fit said cavity and adjustable longitudinally thereof, ducts extending from said cavity, means for directing steam jets across the path of delivery of said jets, and means for adjusting the relation of said steam jets to said ducts.
10. In an oil atomizer, an oil chamber having ducts in its face and a steam chamber having nozzles in its face, one of said faces being depressed at its central part below the plane of the surrounding edge whereby a drip tray is formed when the atomizer is properly disposed in horizontal relation, said chambers being adjustable with respect to one another whereby the direction and separation of said ducts and nozzles with respect to one another is adjusted.

In witness whereof we subscribe our signatures in the presence of two witnesses.
